UNITED STATES PATENT OFFICE.

HARRY BRIDGMAN SMITH, OF NEW YORK, N. Y.

COVERED PAPER BOX.

1,364,899.

Specification of Letters Patent. Patented Jan. 11, 1921.

Application filed June 4, 1920. Serial No. 386,489.

To all whom it may concern:

Be it known that I, HARRY BRIDGMAN SMITH, a citizen of the United States, and resident of New York city, in the county 5 of Kings and State of New York, have invented certain new and useful Improvements in Covered Paper Boxes, of which the following is a specification.

My present invention relates generally to 10 the art of manufacturing covered paper boxes and more particularly to boxes having multiply end walls formed from folded and overlapped portions of the blank or blanks from which the box is made.

15 One object of the invention is to provide a covered paper box of the so called "multiply" end wall type wherein the cover paper is applied to the box shell in a distinctly new way to the end that the strength 20 and appearance of the box are improved and the method of manufacture greatly simplified. Other more or less important objects will appear from the detailed description to follow.

25 I am aware that paper boxes having multiply end walls are old in the art, and I am also aware that cover or wrapper blanks have been applied to such boxes, but my present invention resides in a novel manner 30 of applying the cover or wrapper blank to boxes of the multiply end wall type and wherein portions of the cover or wrapper blank lie in between adjacent faces of the multiply end wall structure of the box.

35 Briefly and more specifically stated, the invention consists of a covered paper box, including a shell blank folded to box form and having multiply end walls formed in part by corner laps and in part by end wings

40 constituting portions of the shell blank, the said corner laps being arranged exteriorly of the end wings, and a cover blank applied to the box and having marginal edges thereof overlying the marginal edges 45 of the side walls as well as the folded corner laps with portions of said overlying marginal edges confined between adjacent faces of the end wings and associated corner laps, the said cover blank also having end wings 50 folded to overlie the outer face and upper edge of each multiply end wall of the box with the marginal edge of each wing adhesively affixed to the inner face of its companion shell blank end wing.

55 In order to enable others skilled in the

art to understand, make and practise my said invention, I will proceed to describe a preferred embodiment thereof in connection with the accompanying drawings, wherein—

60 Figure 1 is a perspective view illustrating one type or construction of shell blank which I may employ in my improved box.

Fig. 2 is a perspective view of the said shell blank and a cover blank with which it 65 may be associated.

Fig. 3 is a perspective view of the shell and cover blanks combined to produce what I have termed an "assembly."

70 Figs. 4, 5, 6, 7 and 8 are perspective views illustrating the several steps or stages in the operation of folding the assembly into box form and,

75 Fig. 9 is a perspective view of the finished box.

80 In the particular type of box elected to illustrate the present invention, A designates the shell blank and B the cover or wrapper blank. The shell blank is usually made of heavy paper board stock such as 85 commonly employed in this art and B is made of relatively light paper, which may be plain or decorated as desired.

85 The box shell blank A is scored or creased longitudinally and transversely as shown to provide a body portion 1, and integral side wings 2, and end wings 3. The side wings 2 are each provided with corner laps 4 at the ends of said wings, the corner laps forming extensions of the side wings. Blanks of this 90 general type are common in the art and I lay no claim thereto except when associated with a cover blank in the manner and to secure the results hereinafter stated.

95 The cover blank B is cut in such a manner as to provide a body portion 5 with integral side wings 6 and end wings 7, the side wings being provided at their ends with extensions 8 adapted to overlie and partially cover the corner laps 4 of the shell blank in the manner presently to be described.

100 In making my improved box with the two blanks A and B above described, I arrange the blanks in superposed and proper registration relation and then inturn the marginal edges 9 of the cover blank over and affix such edges to the corresponding marginal edges of the side wings 2 as well as the marginal edges of the corner laps 4 of the shell blank to provide an "assembly" as 110

illustrated in Fig. 3. In making this assembly I prefer to apply stenciled lines or zones of adhesive to the marginal edges of the shell blank as shown at 10, Fig. 2, although the same result may be secured by applying adhesive to the marginal edges of the cover blank. In some instances, as where so called "tight wrapped" boxes are made I also apply adhesive to the under face of the shell blank, or the adhesive may be applied to the upper face of the cover blank, in order that the cover blank may be adhesively affixed throughout to the face of the shell blank. If so called "loose wrapped" boxes are made, then I apply the adhesive only to the marginal edges of the box shell blank or to the marginal edges of the cover blank, one or the other, as desired.

The assembly having been formed, the side wings thereof are folded up at right angles to the body portion to produce the structure illustrated in Fig. 4 wherein it will be seen that the portions 8 of the side wings of the cover blank extend over onto and cover marginal edges of the corner laps 4 of the shell blank. The end wings 3 of the shell blank are then folded up at right angles to the body portion, leaving the end wings 7 of the cover blank free, as shown in Fig. 5. Then the partially covered corner laps of the assembly are infolded at right angles to the side wings so as to cause portions 9^a of the inturned marginal edges 9 to lie in between adjacent faces of the end wings 3 and corner laps 4 of the shell blank, as more clearly shown in Fig. 6, thus providing neatly covered corner joints at the points where the corner laps are bent or folded and also providing a stronger corner joint construction. Inasmuch as the ends of the corner laps 4 are provided with adhesive, these laps may be readily and securely attached to the end wings 3 of the shell blank when folded as described, suitable pressure being employed after folding the parts in order to securely retain them in position. The assembly having been folded in the manner described and as illustrated in Fig. 6, the end wings 7 of the cover blank are then folded up so as to overlie and neatly cover the multiply end walls of the box as thus formed and the marginal edges of the said cover blank end wings are inturned over the marginal edges of the multiply end walls of the box and adhesively affixed to the inner face thereof to produce the finished structure illustrated in Fig. 9.

If tight wrapped boxes are being formed the end wings 7 of the cover blank will be adhesively attached to the outer face of the end walls of the box structure, but if loose wrapped boxes are being formed, then the end wings will simply overlie the outer face of the end walls, but in either case the marginal edges of the end wings will overlie the

marginal edges of the multiply end walls and will be adhesively attached to the inner face of each end wall.

One of the distinguishing features of my improved box over all prior constructions resides in the fact that the inturned marginal portions 9^a of the cover paper adjacent the corners of the box are confined between the adjacent faces of the end wings 3 and the corner laps 4 of the shell blank when the assembly is folded into box form; a further distinction residing in the fact that the end wings 7 of the cover blank are folded so as to completely cover the multiply end walls including the upper marginal edges thereof so that no raw edges will be left uncovered.

I prefer to make my improved box by first producing a substantially flat assembly as illustrated in Fig. 3 of the accompanying drawings and then folding the assembly into box form as this procedure enables me to make the boxes more expeditiously and more cheaply, although I do not wish to be understood as limiting myself to this exact procedure.

In the illustrated embodiment of my invention I have shown the end wings 7 of the cover blank as having a single thickness width equal in width to their companion end wings 3 of the shell blank and I have also shown the marginal extensions 9^a of the cover blank as terminating short of the extreme ends of the corner laps 4, but I do not wish to be understood as confining myself to this particular construction as the dimensions of the wrapper may be varied somewhat without departing from the true spirit of the invention, a principal feature of which, as heretofore stated, resides in the fact that marginal portions of the cover blank lie in between adjacent faces of the multiply end walls of the folded box shell blank.

While I have herein shown and described a preferred embodiment of my invention, I do not wish to be understood as limiting myself to the precise construction shown, except as I may be limited by the terms of the appended claims and I reserve the right to make such changes or additions in the structure as may fairly fall within the terms of such claims and without departing from the true spirit of the invention.

I claim:

1. A covered paper box including a shell blank folded to box form and having multiply end walls formed in part by corner laps and in part by end wings, constituting portions of the shell blank, the said corner laps being arranged exteriorly of the end wings, and a cover blank applied to the box and having marginal edges thereof overlying the marginal edges of the side walls as well as the marginal edges of the folded

- corner laps, portions of said overlying marginal edges carried by the corner laps being confined between adjacent faces of the end wings and their associated corner laps, 5 said cover blank also having end wings folded to overlie the outer face and upper edges of each multiply end wall of the box with the marginal edge of each wing adhesively affixed to the inner face of its companion shell blank end wing.
2. A covered paper box formed from a substantially flat assembly, consisting of a shell blank having a body portion and integral side and end wings with corner laps 15 at the ends of the side wings, and a cover blank of greater dimensions than the shell blank and also having side and end wings with marginal portions of the side wings inturned over the marginal edges of and adhesively attached to the said shell blank 20 side wings and their corner laps, said assembly being folded into box form with a covered portion of each corner lap inturned at an end of the box and in facial contact 25 with the outer face of its companion shell
- blank end wing to provide multiply end walls, and the end wings of the cover blank overlying the said corner laps and each having its marginal portion folded over the upper edges of the said multiply end walls 30 and adhesively attached thereto.
3. A covered paper box including a shell blank folded to box form and having multiply end walls formed in part by corner laps and in part by end wings constituting 35 portions of the shell blank, the corner laps being arranged exteriorly of the end wings, and a cover blank applied to the shell blank and having marginal edges thereof overlying the marginal edges of the side and end 40 walls of the shell blank as well as the folded corner laps with portions of said overlying marginal edges of the cover blank confined between adjacent faces of the end wings and their associated corner laps when the shell 45 blank is folded into box form.

Signed at New York city, in the county of New York and State of New York, this 27th day of May, A. D. 1920.

HARRY BRIDGMAN SMITH.
